UNITED STATES PATENT OFFICE.

JACOB JACOBS, OF BROOKLYN, NEW YORK.

DESIGN FOR A TILE-BAND.

SPECIFICATION forming part of Design No. 29,003, dated July 5, 1898.

Application filed December 31, 1897. Serial No. 665,243. Term of patent 14 years.

To all whom it may concern:

Be it known that I, JACOB JACOBS, of Brooklyn, in the county of Kings, and in the State of New York, have invented a certain new and original Design for a Tile-Band; and I do hereby declare that the following is a full, clear, and exact description thereof, reference being had to the accompanying drawings, in which—

10 Figure 1 is a perspective view of a tile-band made in accordance with my design, and Fig. 2 is a plan view thereof.

15 The object of my invention is to provide a new and original shape for bands for inclosing tiles and the like; and to this end said invention consists in the design for a tile-band, substantially as hereinafter set forth.

The shape of my band is one formed by a series of scallops or wave-like formations, each of which on the exterior of the band is ²⁰ convex and on the interior thereof is concave.

Having thus described my invention, what I claim is—

The design for a tile-band, substantially as shown and described. ²⁵

In testimony that I claim the foregoing I have hereunto set my hand this 23d day of November, A. D. 1897.

JACOB JACOBS.
